UNITED STATES PATENT OFFICE

165,722

PLASTIC TABLE MAT

Miriam Rodier, New York, N. Y., assignor to Jack Sherman and Morris Post, doing business as Post and Sherman, New York, N. Y.

Application July 13, 1951, Serial No. 15,853

Term of patent 3½ years

(Cl. D92—26)

To all whom it may concern:

Be it known that I, Miriam Rodier, a citizen of the United States, residing at New York, in the county of New York and State of New York, have invented a new, original, and ornamental Design for a Plastic Table Mat, of which the following is a specification, reference being had to the accompanying drawings, forming part thereof.

Fig. 1 is a top plan view of a plastic table mat showing my new design.

Fig. 2 is a cross section view taken on line 2—2 of Fig. 1.

I claim:

The ornamental design for a plastic table mat, as shown.

MIRIAM RODIER.
